FORM FOR PRECASTING INTERRELATED CONCRETE UNITS

Smith Alonzo Rosenberger, Valparaiso, Ind.

Application August 4, 1940, Serial No. 351,364

2 Claims. (Cl. 25—121)

My invention relates to improvements in forms for pre-casting interrelated concrete or cement units. And it more especially comprises the features pointed out in the annexed claims.

The purpose of my invention is to provide interchangeable forms in which the cement or concrete units may be produced; that enables me, with one master form and exchangeable blocks to produce interchangeable units for subsequent assembling in any desired manner; and which by reason of the economies affected in the use of my expedients I am able to produce prefabricated units that may be stored for future use.

With these and other ends in view I illustrate in the accompanying drawing such instances of adaptation as will disclose the broad invention without limiting myself to the specific details shown thereon and described herein.

Fig. 1 is a plan view of assembled units produced by my form.

Fig. 2 is an end elevation of the form.

Fig. 3 is a side elevation partly in section showing end blocks or bulk heads to produce the undercut portion of one of the units.

Fig. 4 is a side elevation partly in section showing the bulk heads reversed end for end to produce the other unit.

Fig. 5 is a detached side elevation showing the use made of a separate wedge block to produce square ends of a unit.

Fig. 6 is a semi-perspective of one of the end blocks or bulk heads.

In practicing my invention I may use whatever equivalences and adaptations of structure that the exigencies of varying conditions may demand without departing from the broad features of the invention.

I use a trough-like form that has an open ended bottom 4 and integral sides 5. The form as a whole is identified by the numeral 3. In order to produce the units 1 and 2 I employ the expedients shown in Figures 3 and 4. In each of these cases the bulk heads 6 are used. In Fig. 3 they produce the under-cut portions 9' of the unit 1 by means of the wedge part 9 and in the case of Fig. 4 they produce the beveled ends 8' of the unit 2 by the inclined end 8. The bulk heads 6 are specially shown in Fig. 6 wherein the beveled ends 8 produce the beveled ends 8' of the unit 2 and the "wedged" portion 9 produces the beveled portion 9' of unit 1.

The bulk heads 6 may be made solid of aluminum or other material, or they may be formed out of sheet metal in which case they will be hollow in the center. If formed solidly of alu-

minum, wood, or other material the portion 9 may be secured to the larger portion having the beveled end 8, by a plate 10 that will hold the part 9 in place against loss. By the use of my bulk heads I am able to form any combination of units 1 and 2 which may be employed as risers and stringers of steps or for any other purpose. The use of the beveled recesses 9' registering with the correspondingly beveled ends 8' interlock the units 2 with the units 1 against displacement. The units 1 and 2 may be made of any desired length. If a bulk head 6 is formed of sheet metal, the approximate outline shown would be followed by bending the sheet where the changes in angle occur. At the beginning and the ending of the sheet, where they meet, they may be electrically or otherwise welded. Should, as stated above, a sheet metal bulk head be used the center would remain open, because the sides 5 of the form will cover the open space and thus prevent cement flowing into it.

Heretofore it has been the custom to produce a separate and distinctive form for each change in shape of a unit. In my case I use a single form with the removable and reversible bulk heads which prevents a multiplicity of forms.

In Figures 3 and 4 the side walls 5 of the form 3 are broken away at the ends showing the units 1 and 2 and also projecting at the center.

I do not limit myself to the specific shape of the bulk heads 6 because these may be varied to suit other cases without departing from the broad spirit of the invention. It is important that a single form with interchangeable and reversible blocks or bulk heads is used.

Any desired form of pins may be used to position the bulk heads in the form at predetermined distances apart and to hold them in place as the cement fills the space between them. The open face of the trough leaves the top edge of a unit exposed for extra troweling.

If the wedge-shaped projection 9 should be used separately, then the bulk head 6 would be formed with one sloping end and a straight portion at the other end still making the bulk head reversible.

In case it is desired to use the bulk head 6 with its attached projection 9 in order to form square ended cement units 7 a wedge block 11 may be placed on the sloping end 8 as shown in Fig. 5.

What I claim is:

1. A reversible bulk head for use in producing articles of the class described which comprises a single length of sheet metal formed into par-

allel sides, a sloping end, a perpendicular end and a wedge shaped extension extending from the perpendicular end, and a sheet metal plate joining the differently formed ends.

2. A reversible bulkhead for use in producing articles of the class described which comprises a member formed with parallel sides, a sloping end, a perpendicular end, a separate

member of wedge shaped contour assembled adjacent the first named member with its narrowest portion approximately abutting the perpendicular end of the first named member, and means for joining the two members with their flat faces on the same plane to constitute a single structure,

SMITH ALONZO ROSENBERGER.
